ATTORNEY

UNITED STATES PATENT OFFICE.

GEORGE E. HARVEY, OF BUFFALO, NEW YORK, ASSIGNOR TO HARVEY RIM & WHEEL COMPANY, OF BUFFALO, NEW YORK.

DISK-WHEEL CONSTRUCTION.

1,427,209.

Specification of Letters Patent. Patented Aug. 29, 1922.

Application filed October 3, 1921. Serial No. 505,039.

To all whom it may concern:

Be it known that I, GEORGE E. HARVEY, a citizen of the United States, residing at Buffalo, county of Erie, State of New York, have invented certain new and useful Improvements in Disk - Wheel Construction; and I do declare the following to be a full, clear, and exact description of the same, reference being had to the accompanying drawings, and to the characters of reference marked thereon, which form a part of this application.

This invention relates to improvements in disk wheel construction for use on motor vehicles, and particularly to cars having at present wood wheels.

The principal object of my invention is to provide steel disks to be used in place of the wood spokes now provided on such cars, and means for mounting the disks on the hub now used with the wooden wheels, without the necessity of having to provide a special form of hub to be used in connection with the original one, or having to remove the latter or disturb it in any way.

Another object is to design the disk wheel structure so that the same sized and number of parts may be used for either the front or rear wheels, the hubs of which as is well known, are different as to length and in other points of construction as well.

A further object of the invention is to produce a simple and inexpensive device and yet one which will be exceedingly effective for the purposes which it is designed.

These objects I accomplish by means of such structure and relative arrangement of parts as will fully appear by a perusal of the following specification and claims.

In the drawings similar characters of reference indicate corresponding parts in the several views.

Fig. 1 is a half cross section of my wheel structure as applied to the front-axle hub of the wheel.

Fig. 2 is a similar view showing the structure applied to the rear-axle hub.

Referring now more particularly to the characters of reference on the drawings, the numeral 1 denotes the standard front-axle hub and 1^a the rear-axle hub.

The former has a flange 2 formed therewith intermediate its ends, which is used to clamp the hub of the wood wheel to, the latter being positioned outwardly of this

flange, and is of course now removed. Similarly the hub 1^a has a flange 2^a further toward the outer end of the hub than the hub 2, so that the wood wheel hub lies thereagainst inwardly thereof, this wood hub being likewise removed.

In applying my disk structure to these axle hubs, I make use of a cup-shaped shell or adapter 3 to slip over the hubs, preferably of pressed metal and larger in diameter than the flanges 2 and 2^a, the rim of which projects outwardly of the wheel and is bent or curled out as at 4, the outer disk 5 of the wheel being bent about the portion 4 and welded thereto, the outer edge of said disk being welded to a fixed rim 6 of any suitable form.

The inner disk 7, likewise secured to the rim 6, has no direct connection with the shell 3, but extends parallel to the back-plate 3^a thereof a certain distance inwardly therefrom, the space therebetween being filled with rings 8, preferably of wood. Both the shell and inner disk are bored to pass over the hubs 1 and 1^a, and edges thereof surrounding the bore being turned or beaded toward each other as shown at 9. In this manner, since the disk structure is adapted to be mounted onto the front axle hub 1 from the outer end thereof, the bead or curl 9 on the inner disk will then fit the fillet 10 at the junction of said hub with its flange 2.

The rear axle hub however receives the disk structure thereon from the inner end thereof, so that in this case the bead 9 on the cut will fit the inner fillet 10^a between said hub and its flange. Thus it will be seen that identically formed structures may be used for both the front and rear hubs. The shell and inner disk and rings or inserts 8, may be secured to the flanges 2 and 2^a by the same bolts 11 originally used to hold the wood wheel hubs. In the rear wheel, these bolts of course also hold the brake drum 12, which rests against the inner disk 7, the latter being positioned to allow the position of the drum being undisturbed from its original setting.

I also aim to use the hub caps 13 and 13^a for the front and rear hubs of such length that they may be connected to plates 14 which will cover the space between the shell 3 and the hubs 1 and 1^a, and effectively conceal the bolts.

I have particularly described only outer

and inner disks as being used, but as shown, an intermediate disk 15 extending diagonally between the outer and inner disks is also preferably incorporated, which however does not change the construction or set-up of the wheel structure in any material manner.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A disk wheel structure including inner and outer disks, a shell adapted to fit over a hub, the outer disk being fixed to the rim-edge of the shell but the inner disk being spaced inwardly of the shell, and filler members between the shell and inner disk.

2. In combination with a hub having a flange projecting outwardly therefrom, a cup-shaped shell having an inner bore adapted to fit over the hub and another bore adapted to receive the flange therein, an

outer disk fixed to the outer edge of the shell, an inner disk spaced from the inner end of the shell, filler blocks about the hub between the shell and inner disks, and means for securing said inner disk, filler blocks and shell to the flange.

3. In combination with a hub having a flange projecting outwardly therefrom, a cup-shaped shell having an inner bore adapted to fit over the hub and another bore adapted to receive the flange therein, another disk fixed to the outer edge of the shell, an inner disk spaced from the inner end of the shell, filler blocks about the hub between the shell and inner disks and bolts passing through said shell, filler blocks, inner disk and flange to hold the same together in driving relation.

4. In combination with a hub having a flange projecting outwardly therefrom, a cup-shaped shell having an inner bore adapted to fit over the hub and another bore adapted to receive the flange therein, the shell projecting outwardly of the flange, a hub cap on the hub, and a plate fixed on said cap and extending to the outer rim-edge of the shell to enclose the space between the hub and shell rim.

In testimony whereof I affix my signature.

GEORGE E. HARVEY.
